REGULATING THE WORKING OF INTERNAL COMBUSTION ENGINES

Filed May 5, 1927

Inventor
Thomas D. Kelly
By
James L. Potts
Attorney

UNITED STATES PATENT OFFICE.

THOMAS DANIEL KELLY, OF LONDON, ENGLAND.

REGULATING THE WORKING OF INTERNAL-COMBUSTION ENGINES.

Application filed May 5, 1927, Serial No. 189,113, and in Great Britain March 17, 1927.

For the purpose of my present invention, by cutting off the fuel or combustible mixture supply to the spaces on top of the larger diameter piston or between the pistons (by 5 means of suitable valves connecting with the inlet pipes), that portion of the engine then only draws in air for cooling through inlet valves, whereby the number of impulses per cylinder can be regulated as desired and any 10 one or all the spaces used for creating power.

My invention will be more fully understood from the following description aided by the annexed drawing which is a sectional elevation of a portion of an engine showing a cylinder A of two diameters A, B, the portion B being eccentric to the portion A.

At near one end of the portion A is positioned a single piston C connected by a rod D to the crank E of the driving shaft F and also 20 in the larger and eccentric portion B and also in the portion A is positioned a double diameter piston G, H, the portion G fitting the cylinder portion A whilst the portion H which is eccentric to the portion G fits the 25 portion B of the cylinder, and such piston G, H from the greater diameter H is connected by a rod 1 to a crank J on the crank shaft F, the two cranks being oppositely arranged 30 so that the pistons C and G, H move towards and away from each other.

The fuel or combustible mixture inlet to the chamber K between the two pistons C and G, H and the inlet to the chamber L above the piston G, H are connected by a pipe 35 M and this in turn is connected by a branch N to the carburetor P.

S is the sparking plug; T the exhaust; V V 40 separate air inlet valves, all being connected with the spaces K, L.

In the pipe M are fitted two control valves V V positioned as required.

In action the engine runs as a two or four stroke cycle and the various functions are performed in the spaces K, L, as will be 45 well understood, but should it be desired to reduce the power by closing one of the valves V the combustible mixture will be cut off from the corresponding space and the recip-

rocating action of the piston will draw air through the valve V into the spaces and cool 50 the engine reducing the number of explosions (power units) in each cycle.

As will be understood from the description and drawing, the engine differs in having opposed pistons from double acting engines 55 having pistons and cylinders of single diameters with ordinary piston rods passing through the stuffing box and also from engines having tandem cylinders and pistons, both of which have been proposed, and in 60 each case two explosions are produced in one cylinder, and the power obviously can be varied by cutting out one of the combustion chambers to regulate the power output and permit air to enter the same, as before 65 set forth.

What I do claim as my invention and desire to secure by Letters Patent is:—

In an explosive engine, a double diameter cylinder, a double crank shaft, a single 70 diameter piston connected to one of the cranks and mounted in the cylinder, a double diameter piston mounted in the cylinder and operably connected to the other crank, the reduced end thereof cooperating 75 with the first piston and providing an explosive chamber in the cylinder between said pistons, there being provided in the enlarged diameter portion of the cylinder above the similar diameter portion of the 80 piston a second combustion chamber, a valve-controlled air inlet port and a valve-controlled exhaust port provided for each combustion chamber, a main fuel supply, two conduits leading therefrom and connected 85 respectively to the two combustion chambers, in-take valves controlling said entrances to the combustion chamber, and two selectively operated valves mounted in the conduit whereby either one of the combustion chambers can be isolated from said conduit and the fuel cut off selectively therefrom.

In testimony whereof I have hereunto set my hand.

THOMAS DANIEL KELLY.
